ABSTRACT

A firing means for launching a model rocket utilizing a solid state power means for supplying an electrical firing voltage and current to an ignitor circuit of the rocket, upon signal from a remote control switch.

ATTORNEY

1

FIRING MEANS FOR A MODEL ROCKET

BACKGROUND OF THE INVENTION

This invention relates generally to model rockets and more particularly relates to a battery powered firing means for the launching of a model rocket. More particularly, the invention relates to a firing circuit having a solid state power means for supplying ignition current for a model rocket.

In the past, the electrical firing voltage and current required for igniting a model rocket were controlled from a remote control switch located at one end of a cable. The opposite end of the cable was connected to the rocket ignitor circuit and a standard electrical battery. Turning the switch "on" connected the battery directly to the ignitor circuit of the rocket. Generally, in order to provide sufficient voltage across the ignitor circuit, it was necessary that the cable length not exceed 10 feet. The subject invention, on the other hand, appreciably reduces the high current path between the battery and the ignitor circuit and thereby enables the cable length between the remote control switch and the ignitor circuit, to be substantially increased, without effecting the desired voltage across the ignitor circuit. Therefore, by utilizing the greater extended length of the cable, the possibility of the explosion of the rocket fuel causing injury to the operator of the remote control switch is substantially reduced, if not entirely eliminated. Moreover, by shortening the high current path, the frequency of battery replacement may be reduced.

SUMMARY OF INVENTION

The subject invention comprises a firing means interposed between a rocket ignitor circuit and a remote control switch. A cable having a substantial extended length is connected on one end to the remote control switch and on the opposite end to the firing means. Upon switching the remote control switch to its on-position, a small current flows to the firing means through the cable, which in turn causes a substantially larger current to flow to the rocket ignitor circuit through a substantially smaller current path. The larger current is sufficient to cause ignition of the fuel contained in the model rocket which launches the rocket.

Accordingly, the primary object of the subject invention is to provide a short path for the high electrical current required for firing the rocket, thereby reducing electrical power losses.

Another object is to provide means for reducing the frequency of electrical battery replacement.

Another object is to provide a long current path for a small electrical current to provide a power "on" signal from a remote point with respect to the launch pad of the rocket, and a substantially shorter current path for a larger electrical current required for firing the rocket.

Still another object is to use a solid state static switch means for connecting and disconnecting electrical voltage and current to the ignition of a model rocket upon signal from a remote control switch.

Still another object is to provide means for faster ignition of a model rocket.

These and other objects and advantages will become apparent from the illustrations in the accompanying drawings and the following specifications and claims.

BRIEF DESCRIPTION OF THE DRAWINGS

Referring to the drawings in which the same characters of reference are employed to indicate corresponding or similar parts throughout the several figures of the drawings;

FIG. 1 is a perspective view of a firing circuit for the ignitor of a model rocket shown in phantom, embodying the principles of the invention; and

FIG. 2 is an electrical schematic diagram of the firing circuit.

2

DESCRIPTION OF THE PREFERRED EMBODIMENT.

Referring now to FIGS. 1 and 2 of the drawings, the reference numeral 10 indicates generally a control means for firing an ignitor means 11 of a model rocket 12 (shown in phantom in FIG. 1). The control means 10 comprises a firing circuit 14 controlled by a remote control switch 16. The control switch 16 is linked to the firing circuit 14 by a cable 18 having a substantial extended length.

10 The firing circuit 14 comprises a static switch means such as a transistor 20, having a base 1, emitter 2 and a collector 3. In operation, transistor 20 has an on-condition and an off-condition. The transistor 20 is powered from a battery 22 having a positive terminal 23 and a negative terminal 24. The cable 18 comprises leads 25, 26, connected respectively to the base 1 and collector 3 of the transistor 20. The opposite end of lead 25 is connected to contact 28 of switch 16 and the opposite end of lead 26 is connected to a terminal 30. A contact 32 of switch 16 is connected to a terminal 34.

20 A resistor 36 is connected between the base 1 and the positive terminal 23 of battery 22. The emitter 2 of transistor 20 is connected to a terminal 38. A terminal 40 is connected to the ignitor means 11 of the rocket 12 via lead 41. The positive terminal 23 of the battery 22 is connected to the ignitor means 11 via lead 41'.

The battery 22 as shown is external from the firing circuit 14. Leads 42, 42' extend out from the firing circuit 14 for removable connection onto the battery 22. The rocket ignitor means 11 is also external from the firing circuit 14. Leads 41, 41' extend out from the firing circuit 14 for connection onto points or terminals of a micron wire of the ignitor means 11. Alligator clips or other suitable means for removable connections, may be used for connecting leads 41, 41' and leads 42, 42' respectively to the ignitor means 11 and battery 22.

30 An arming bar 43 pressfits into terminals 30 and 34 to link the switch contact 32 of switch 16 with cable lead 26. Another arming bar 44 pressfits into terminals 38 and 40 to link the ignitor means 11 with the emitter 2 of transistor 20. In operation, both arming bars 42 and 43 must be pressfitted into place. If either bar is not in place the rocket will not be ignited.

40 The remote control switch 16 has an on-position and an off-position (shown in FIG. 2). When remote control switch 16 is in the off-position, transistor 20 is biased "off." When switch 16 is manually switched to its on-position, current flows through cable 18 to create a negative voltage between the transistor base and collector of sufficient magnitude to cause transistor 20 to switch from its off-condition to its on-condition. In the on-condition, ignitor current flows to the ignitor means 11 through the small electrical path from the battery 22, the transistor 20 and leads 41 and 41'. This causes ignition of the rocket fuel and launching of the model rocket 12.

45 Although other transistor arrangements may be used, transistor 20 is shown in FIG. 2 as a PNP. The cable 18 may be a 26-gauge wire and a length exceeding 20 feet. For a number 26-gauge wire a cable length of 200 feet or more may be used.

The foregoing specification and description are intended as illustrative of the invention, the scope of which is defined in the following claims.

I claim:

1. A control means for a model rocket, said model rocket including an ignitor for igniting the fuel to launch the rocket, said control means comprising:
  - 65 a manual switch means having an on-position and an off-position;
  - a battery means having a first terminal and a second terminal;
  - 70 a transistor including a base, emitter and collector, said transistor having an on-state and an off-state, said transistor being in the on-state when said manual switch is in the on-position and in the off-state when said manual switch is in the off-position;
  - 75 a resistor means connected between one terminal of said battery and the base of said transistor;

a cable including a first wire and a second wire, said first wire being connected between said battery means and said manual switch and said second wire being connected between said transistor and said manual switch, so that a biasing voltage is applied across said resistor means when said manual switch is on the on-position and thereby provide a first current path for a first current to cause said transistor to switch to the on-condition, and

5 a connector means for connecting said transistor means with said ignitor said connector means and said ignitor and said transistor when in the on-state, providing a second current being substantially greater in magnitude than the first current, said first current path being substantially longer than said second current path, said second current flowing to said ignitor when said transistor is in the on-state.

2. The control means of claim 1, includes:

a removable arming bar connected between said cable and said manual switch means, whereby the removing of said arming bar prevents flow of said first current.

3. The control means of claim 2 further includes:

a second arming bar connected between the transistor and said second connecting means whereby the removing of said second arming bar prevents flow of said second current.

4. The control means of claim 1 includes means for disconnecting said transistor from said ignitor and means for disconnecting said battery from the manual switch.

5. The control means of claim 1 includes means for disconnecting said battery from the manual switch.

6. A control means for a model rocket, said model rocket including an ignitor for igniting the fuel to launch the rocket, said control means comprising:

a manual switch having an on-position and an off-position; an electrical power means; a solid state switching means having an input and an output, said switching means having an on-state and an off-state, said switching means being in said on-state and off-state when said manual switch is respectively in the on-position and off-position, said ignitor being connected to said output;

10 a cable connected between said switching means and said manual switch, said cable providing a first current path for a first current after the manual switch is switched to the on-position, to apply a voltage across said input and cause said switching means to switch into the on-state; and

15 a connector means for connecting the output of said switching means with said ignitor to provide a second current path for a second current, said first current path being substantially longer than said second path, said second current being greater than said first current, said second current flowing to the ignitor when said switching means is in the on-state.

20 25 7. The control means of claims 6, wherein said switching means comprises a transistor having a base, emitter and collector, said transistor being biased "on" when the switch is in the on-position and biased "off" when the switch is in the off-position.
